Primary Examiner — Karen E Kearney*Assistant Examiner* — Dina Michelle Hoeynck(74) *Attorney, Agent, or Firm* — Sughrue Mion, PLLC(57) **CLAIM**

The ornamental design for a camera mount coupler as shown and described.

DESCRIPTION

FIG. 1 is a front perspective view of a camera mount coupler showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom perspective view thereof; and,

FIG. 9 is a front view thereof showing a state in which a camera mount and a surveillance camera are coupled by the camera mount coupler.

The broken lines in FIG. 9 depict portions of the environment and form no part of the claimed design.

1 Claim, 9 Drawing Sheets
